HUGH WAIN, OF RAVENNA, OHIO.

Letters Patent No. 83,344, dated October 20, 1868.

IMPROVED GAS-MACHINE.

The Schedule referred to in these Letters Patent and making part of the same

To all whom it may concern:

Be it known that I, HUGH WAIN, of Ravenna, in the county of Portage, and State of Ohio, have invented certain new and useful Improvements in Gas-Machines; and I do hereby declare that the following is a full and complete description of the construction and operation of the same, reference being had to the accompanying drawings, making part of this specification, in which—

Figure 1 is a side view of the apparatus.

Figure 2, a top view of the inside.

Figure 3, a vertical section.

Like letters of reference refer to like parts in the different views.

This invention relates to the production of illuminating-gas by compelling a current of air through any of the compounds known as hydrocarbon-oil.

In fig. 2, A represents an outer shell or cylinder, in which is placed an oil-tank, B, on the brackets *a*, whereby it is elevated above the floor of the cylinder.

Within said tank is erected a concentric wall, C, thereby making said tank of a narrow, circular form, C', and which is elevated above the floor of the sides B C, as shown in fig. 3.

The bottom of said circular tank is perforated with holes, *b*, the purpose of which will hereinafter be shown.

D, fig. 1, is a gasometer or receiver, constructed and arranged in the ordinary way, and which is put in connection with the shell or cylinder A by means of the gas-pipe E.

On the opposite side of the cylinder is a blower, F, and which is put in connection with the cylinder A by means of the air-pipe G, the inner end of which terminates in the space F', immediately under the tank.

The space H, surrounding the oil-tank B, is filled with ashes, to serve as a poor conductor of heat, whereby an equilibrium of temperature is obtained to the apparatus and its contents, so that it shall remain unaffected in its operation by the vicissitudes of the weather.

I is a pipe, whereby the machine is charged with oil, and J the exit-pipe, leading from the receiver to the burner.

The practical operation of this machine is as follows, viz:

The tank B is filled with oil until it reaches the safety-pipe K, which, as will be observed, allows the escape of oil before it reaches the top of the tank. Hence the tank cannot be filled so as to run over into the adjoining compartment, and thereby injure the apparatus. The blower referred to is now actuated by any mechanical appliance, and thereby a current of air

is forced into the cylinder through the pipe G, which, entering the mass of oil at the bottom, is blown through it, first passing through the perforation, whereby it is more diffused, and consequently so atomized as to bring it more intimately in contact with the oil, from which it becomes charged with the hydrocarbonic element it contains, by this means converting the air into illuminating-gas, which escapes, as fast as generated, from the upper space above the oil to the gasometer or receiver D, through the pipe E, entering at the bottom, and ascending, in the pipe, to the upper space of the float or cap of the gasometer, from which it is conducted out to the burner by the pipe J.

As an equal and uniform temperature is essential to a proper conducting of the process, so that the fullest and most satisfactory results shall be obtained, the oil is kept surrounded by ashes, which, being a good non-conductor of heat, contribute largely to a successful termination of the process.

I am aware that gas has been generated by a similar process as the one above described, but the apparatus employed requires the use of water, for the purpose of equalizing the temperature of the process. This use of water is a matter of much trouble and care, for the reason that the vessels holding the water must be made very tight, to prevent leaking, and proportionately strong, which is attended with a large expense, and therefore renders the machine too expensive for general use; also, in cold weather, the water freezes, and, in consequence of its expansion, bursts the vessels, thereby so injuring the apparatus as to render it, for the time, useless; but, by constructing this machine with a view of using ashes, or their equivalent, for the purpose specified, and in the manner as above described, no care need be taken to make the apparatus tight, for holding the ashes. Hence a much less expensive machine can be made. The ashes are also a better non-conductor of heat than water, and therefore answer a much better purpose in this respect, and, in cold weather, do not freeze, to the danger of bursting the apparatus.

What I claim as my improvement, and desire to secure by Letters Patent, is—

The arrangement of the cylinder A, tank C, provided with induction and exhaust-pipes, and having the space H filled with a poor conducting-material, in combination with the perforated bottom and gasometer D, as and for the purpose substantially as described.

HUGH WAIN.
